UNITED STATES PATENT OFFICE.

THEODORE C. STEIMER, OF PITTSBURG, PENNSYLVANIA.

DESIGN FOR A GLASS VESSEL.

41,092.

Specification for Design.

Patented Jan. 17, 1911.

Application filed October 6, 1910. Serial No. 585,730. Term of patent 14 years.

To all whom it may concern:

Be it known that I, THEODORE C. STEIMER, a citizen of the United States, residing at Pittsburgh, in the county of Allegheny and State of Pennsylvania, have invented a new, original, and ornamental Design for Glass Vessels, of which the following is a specification, reference being had to the accompanying drawings, forming part thereof.

Figure 1 of the drawings shows in eleva-

tion a glass vessel embodying my design; Fig. 2 is a plan view of the bottom of the vessel.

I claim:

The ornamental design for a glass vessel as shown.

THEODORE C. STEIMER.
